UNITED STATES PATENT OFFICE.

HENRY STERN, OF NEW YORK, N. Y.

JEWELRY.

Application filed November 22, 1924. Serial No. 751,515.

To all whom it may concern:

Be it known that I, HENRY STERN, a citizen of the United States, and resident of New York, in the county of New York and State of New York, have invented certain new and useful Improvements in Jewelry; and I do hereby declare the following to be a full, clear, and exact description of the invention, such as will enable others skilled in the art to which it appertains to make and use the same.

This invention relates to improvements in jewelry and while my improvements are particularly adapted to finger rings, they may be applied also to other articles of jewelry.

One object of the invention is to provide a reversible setting, the respective faces of which may present different appearances or provided with different jewels, emblems or insignia, and which shall be so pivotally mounted that it shall normally fit snugly within and be surrounded by an open frame which forms a part of the article of jewelry, so that when the improvements are applied to a finger ring, the finger of the wearer will serve to prevent the setting from turning, and to provide simple means to hold the setting from turning when the ring or other article of jewelry is not in use or which will operate as supplementary means to assist turning of the setting when the article of jewelry is in use.

With this and other objects in view, the invention consists in certain novel features of construction as hereinafter set forth and pointed out in the claims.

In the accompanying drawings;

Figure 1 is a perspective view illustrating the application of my improvements to a finger ring;

Figure 2 is an enlarged sectional view;

Figure 3 is a sectional view taken at right angles to Figure 2, and

Figure 4 is a face view.

When my improvements are applied to a finger ring as illustrated in the drawings, the ring 1 is made with an open frame 2 having a shape conforming to the peripheral outline of the setting to be employed. In the drawing, the frame 2 is shown as having a general rectangular shape but it is apparent that it may be circular, elliptical or any other desired shape.

Within the frame 2 and snugly embraced thereby, the setting 3 is pivotally mounted,

and the setting per se may have a band 4 around the same, said band being made with a corrugation 4^a to engage in a groove 4^b in the setting per se. The pintles 5 by 60 which the setting is pivotally mounted in the open frame may be carried by the latter and caused at their inner ends to pivotally engage the band 4 of the setting at diametrically opposite points. In the drawings, the setting is shown as being pivotally mounted centrally between its ends, but it is evident that the pintles may be located at respective ends of the setting when the same is elongated in form, if desired. 70

My improvements permit the interchangeable display of different appearances of settings, as one side of the setting may carry a jewel, insignia or symbol and the other side either plain or provided with a different jewel, insignia or symbol. In the drawing, one side of the setting is shown as having the initial "S" thereon and the other side as carrying a jewel or star-shaped object 6. 75

By mounting the setting within an open frame on the ring, said setting will, when the ring is being worn, be prevented from swinging or turning, by contact with the finger of the wearer and the setting may 85 therefore lie close to the finger and not project unduly from the ring.

As supplementary means to prevent the setting from turning when the ring or other article of jewelry is being worn, and to prevent turning of the setting when the ring or other article of jewelry is not in use, a suitable spring catch may be employed. In the present instance, a spring catch 7 is shown. This may consist of a spring secured to the frame 2 opposite a recess 8 therein and having a rounded end portion 9 to engage in the groove formed by the corrugation 4^a in the setting band 4. 90 95

Slight changes might be made in the details of construction of my invention without departing from the spirit thereof or limiting its scope and hence I do not wish to restrict myself to the precise details herein set forth. 100

Having fully described my invention what I claim as new and desire to secure by Letters Patent, is:—

1. A finger ring structure, comprising a band including an open frame, a reversible setting pivotally mounted in said open frame and substantially filling the same so 110

that one face of said setting will normally be approximately flush with the inner edges of the frame, whereby said setting will be prevented normally from turning by engagement with the finger of the wearer, and a spring catch interposed between said pivoted setting and said frame.

2. A finger ring structure, comprising a band including an open frame, a reversible setting pivotally mounted in said open frame and substantially filling the same so that one face of said setting will normally

be approximately flush with the inner edges of the frame, whereby said setting will be prevented normally from turning by engagement with the finger of the wearer, and a spring catch interposed between said pivoted setting and said frame, said spring catch being located to engage a part of said setting at approximately right angles to the pivot axis of the latter. 15 20

In testimony whereof, I have signed this specification.

HENRY STERN.
